UNITED STATES PATENT OFFICE

115,239

DESIGN FOR A BELL HOUSING FOR ELECTRICALLY OPERATED ALARMS

Gustaf Schwartz, Chicago, Ill., assignor to Certified Burglar Alarm Systems, Inc., Chicago, Ill., a corporation of Illinois

Application February 12, 1938, Serial No. 75,100

Term of patent 14 years

To all whom it may concern:

Be it known that I, Gustaf Schwartz, a citizen of the United States, residing at Chicago, in the county of Cook and State of Illinois, have invented a new, original, and ornamental Design for Bell Housing for Electrically Operated Alarms, of which the following is a specification, reference being had to the accompanying drawing, forming a part thereof.

In the drawing:

Figure 1 is a perspective view of a bell housing

for electrically operated alarms showing my new design, the dominant feature of the design being a dome-shaped housing having a star-like insignia displayed thereon, and

Figure 2 is a side view thereof.

I claim:

The ornamental design for a bell housing for electrically operated alarms, substantially as shown and described.

GUSTAF SCHWARTZ.
